(57) **CLAIM**

The ornamental design for a sound amplifying apparatus with adjustable headband for enhancing the hearing of a user, as shown and described.

DESCRIPTION

Applicant filed U.S. patent application Ser. No. 29/316,415 on Sep. 23, 2009, now abandoned, and incorporated herein by reference in its entirety.

FIG. 1 is a perspective view of a sound amplifying apparatus with adjustable headband for enhancing the hearing of a user, showing my new design;

FIG. 2 is a front elevational view thereof;

FIG. 3 is a left side elevational view thereof, the right side elevational view being a mirror thereof;

FIG. 4 is a rear elevational thereof;

FIG. 5 is a top plan view thereof; and,

FIG. 6 is a bottom plan view thereof.
